(57) **CLAIM**

The ornamental design for a tire, as shown and described.

DESCRIPTION

FIG. 1 is a perspective view of a tire showing my new design, it being understood that the pattern is repeated uniformly throughout the circumference of the tread.

FIG. 2 is a front view thereof. The top and bottom views are identical.

FIG. 3 is a rear view thereof.

FIG. 4 is a left side view thereof.

FIG. 5 is a right side view thereof; and,

FIG. 6 is a detail view from upper 6-6 to lower 6-6 of FIG. 2.

The broken lines illustrate environmental subject matter only and form no part of the claimed design. The dash-dot-dash lines indicate a boundary of the claimed design and are not part of the claimed design. The surface shading lines and stippling in the drawings depict the character or contour of the surfaces represented and are not part of the claimed design.
